UNITED STATES PATENT OFFICE

150,434

DESIGN FOR AN AIRPLANE

Kenneth F. Lovejoy, Pittsburgh, and David Barr
Peat, Dravosburg, Pa.

Application February 15, 1946, Serial No. 126,583

Term of patent 14 years

(Cl. D71—1)

To all whom it may concern:

Be it known that we, Kenneth F. Lovejoy and David Barr Peat, both citizens of the United States, residing respectively in Pittsburgh, in the county of Allegheny and State of Pennsylvania, and Dravosburg, county of Allegheny, and State of Pennsylvania, have invented a new, original, and ornamental Design for an Airplane, of which the following is a specification, reference being had to the accompanying drawings, forming part thereof.

Figure 1 is a side elevational view of an airplane showing our design;

Figure 2 is a front view;

Figure 3 is a top plan view; and

Figure 4 is a rear perspective view thereof, the wing tips being broken away for convenience of illustration.

We claim:

The ornamental design for an airplane, as shown.

KENNETH F. LOVEJOY.
DAVID BARR PEAT.
